UNITED STATES PATENT OFFICE.

ALBERT BAUMGARTEN, OF FREEPORT, ILLINOIS.

MECHANISM FOR CORKING BOTTLES OR LIKE RECEPTACLES.

SPECIFICATION forming part of Letters Patent No. 668,478, dated February 19, 1901.

Application filed August 2, 1900. Serial No. 25,601. (No model.)

To all whom it may concern:

Be it known that I, ALBERT BAUMGARTEN, a citizen of the United States, and a resident of Freeport, in the county of Stephenson, State 5 of Illinois, have invented certain new and useful Improvements in Mechanism for Inserting Corks into Bottles or Like Receptacles, of which the following is a full, clear, and exact description.

10 The invention relates to devices for inserting corks into the necks of bottles and the like, and designs, primarily, to provide a simple construction of mechanism which can be quickly operated and, furthermore, to provide improved mechanism whereby a bottle 15 can be securely held in proper position beneath the case while the mechanism for inserting a cork is being operated. In devices of this class it has been customary to provide 20 a base or support whereby a bottle was supported and held while the mechanism for inserting corks was being operated. In some instances such base or support was movable, so the bottle could be brought into position 25 beneath the mechanism for inserting a cork and to provide for holding bottles of different heights, and in other instances the plunger casing or support was movable to permit the plunger and casing to be shifted and 30 brought into proper relative position with respect to the bottle. Both of such constructions were of necessity somewhat large and 35 cumbersome. The present invention designs to avoid the necessity of mounting either the bottle-support or the plunger-frame in a manner free to move with respect to each other.

One feature of the invention consists in providing a clamping mechanism adjacent the plunger-casing, whereby the necks of bottles 40 of all thicknesses or heights may be conveniently, quickly, and securely held in proper position to have a cork inserted in the mouth thereof. In practice I have found that a clamping mechanism secured to the plunger 45 casing or support can be made to securely retain a bottle against displacement while the cork is being forced into the bottle-neck by the plunger. By employing a clamping mechanism secured to the casing to hold the bottle-neck the plunger support or casing can be 50 rigidly secured, and such mechanism will

serve to securely hold bottles regardless of thickness or height in proper position beneath the plunger-casing while the plunger is being operated.

55

It has heretofore been customary to employ a long lever for imparting longitudinal movement to the plunger. The present invention further designs to provide a simple construction wherein the necessity of employing a long operating-lever is avoided and to provide a simple, effective, and compact operating mechanism.

With such object in view the invention further consists in providing intermeshing teeth 65 intermediate the plunger and lever, whereby the desired leverage is obtained and the necessary force may be applied to the plunger for inserting a cork into the neck of a bottle. In such construction a short lever and an ex- 70 tended throw thereof may be used, thus providing a smaller, more compact, and simpler arrangement than was heretofore used.

The invention further consists in providing a casing for the plunger wherein the operating-lever is pivotally sustained and which is formed of separate sections secured together. Such construction affords a construction 75 which is inexpensive of construction and which permits the operating parts to be readily and easily placed in proper relative position and held in such relation during the operation.

The invention further consists in the several novel features of construction hereinafter described, illustrated in the accompanying drawings, and more particularly defined by claims at the conclusion hereof.

In the drawings, Figure 1 is a view in side elevation of a corking apparatus embodying 90 the preferred form of the invention. Fig. 2 is a view in horizontal section on line 2 2 of Fig. 1. Fig. 3 is a side view, a section of the casing being removed to show the parts within, the operating-lever and plunger being 95 shown in position assumed after a cork has been forced into a bottle. Fig. 4 is a front elevation. Fig. 5 is an inverted plan. Fig. 6 is a detail sectional view through the casing-sections at line 6 6 of Fig. 3.

100

A denotes an inclosing casing or frame designed to contain the several parts and re-

tain them in operative relation. The casing is preferably formed of separate vertical sections 10 and 11, secured together, as by screws 12, and said sections form sides between which 5 the operating parts of the mechanism for inserting corks fit and are held. By forming the casing in sections the operating parts within the casing may be readily assembled and placed in position, and when the sections 10 have been secured together said parts will be held in proper relative position. In practice it is customary to provide the casing with means whereby it may be secured to a fixed support, such as a table, counter, or shelf. 15 Such means usually comprise a rest or lug *a*, formed integrally with one of the casing-sections and adapted to rest upon a table or like support, and a jam-screw 2, extended through a lug *a'*, formed on one of the casing-sections. 20 3 is a washer or pressure-plate carried by jam-screw 2 and adapted to engage the under-side of a fixed support and secure the casing in desired position.

Casing-section 11 is formed with an extension or lug 13, wherein is secured a bolt or pin 14, whereon the jaws B and B' of the bottle-holder are pivotally secured. Each of the jaws B and B' is provided with ears 15, encircling pin 14, and is formed with a curved 30 central portion formed to fit around a bottle-neck, and the jaws are provided with an elastic lining-strip 16, arranged to impinge against the bottle-neck. The distal end of jaw B is provided with a stud 17, which is projected through and held within a horizontal slot 18, formed in a depending portion 19 of casing-section 10. The distal portion of jaw B' is likewise provided with a stud 20, which projects through and is held within a horizontal 40 slot 21, formed in depending portion 19 of casing-section 10. Such slots and studs retain the jaws against vertical movement. A hand-lever C is pivotally sustained in position at the side of the casing by a pivot-pin 45 *c*. Studs 17 and 20 of the jaws B and B' are also projected, respectively, into slots 22 and 23, formed in hand-lever C upon opposite sides of pivot *c* thereof. The lever-pivot is located centrally between the studs, so that 50 when the lever is shifted both of the jaws are shifted toward each other to cause the bottles to be positioned centrally beneath the casing.

The operation of the mechanism for holding bottles is as follows: Assuming the parts to be in the position shown in full lines in Fig. 1 and a bottle to have been placed between the jaws B and B', the operator will swing the handle C' of lever C backwardly to 55 the position shown in dotted lines in Fig. 1, and such shift will cause the lever C to swing about its pivot *c* and shift studs 17 and 20 and jaws B and B' toward each other and force the lining-strips 16 firmly against the bottle-neck. The bottle-neck will then be securely held beneath the corking apparatus in position to receive a cork. A reverse shift of the

hand-lever C will return the parts to normal position and release the bottle from the bite of the jaws of the bottle-holder.

70

Within the casing A a cylindrical guide or way 24 is formed, wherein a plunger D is held in a manner free to slide longitudinally, and the lower portion thereof is tapered, as at 25, to compress a cork sufficiently to enter the 75 neck of a bottle. Above socket 25 in the front of casing A an opening 26 is formed, through which a cork may be placed into the guide 24 or socket 25 in position to be forced downwardly by plunger D. The socket 25 has an 80 open lower end, wherethrough a cork can pass into the mouth of a bottle held in position against or in close proximity to the casing.

E is an operating-lever provided with a suitable handle *e* and pivot studs or trunnions 85 28, projected laterally therefrom and held in journals 29, formed in lugs 36, formed integral with the casing-sections. The operating-lever is held between lugs 36 of the casing-sections and is also provided with a segmental 90 gear or gear-teeth 31 adjacent its pivot, which intermesh with corresponding rack-teeth 32, formed on the plunger. In normal position the operating-lever extends backwardly from the casing and rests upon lug *a* and when in 95 such position serves to retain plunger D in its upward position.

The operation of the corking apparatus is as follows: Assuming the parts to be in normal position, (shown in Fig. 1,) a bottle being 100 held in proper position beneath the tapering socket 25 by jaws B and B', and a cork to have been placed in socket 25 through opening 26, the operator will swing lever E forwardly about its pivot, such oscillation causing the 105 intermeshing teeth of the lever and plunger to impart a downward movement to the plunger. The plunger during such downward movement will engage the cork and force the same through tapering socket 25 and into the 110 bottle-neck. While passing through tapering socket 25 the cork will be compressed so it will readily enter the bottle-neck. A reverse shift will restore the plunger to normal 115 position in the casing and in readiness for a succeeding operation.

The invention possesses several important advantages. The clamping mechanism arranged beneath the casing is a simple mechanism which can be quickly and conveniently operated and whereby bottles of all sizes will be securely held in proper position centrally beneath the socket of the casing. The mechanism for shifting the plunger is simple and inexpensive of construction, and 125 by employing intermeshing teeth to impart movement to the plunger a sufficient leverage and length of stroke is had without the necessity of employing a very long lever, such as is now in use. The casing formed 130 of sections fitted together provides a simple means for retaining the operating parts in operative relation and in such manner that these parts may be readily assembled, and,

furthermore, when separate sections are employed the operating-lever, segmental gear, and pivot-studs may be formed integral.

The entire apparatus is simple and can be 5 readily secured to any desired support, and the construction is a very compact one.

The invention, so far as I am aware, is the first instance wherein clamping mechanism conveniently secured to the plunger-easing 10 has been used to hold the upper portion of a bottle in position in a device used for inserting corks, and this mechanism I have found in practice to be an exceptionally-advantageous construction.

15 The invention is not to be understood as restricted to the construction shown and described, but may be varied within wide limits without departing from the spirit of the invention. So, also, the features thereof may 20 be employed severally without its adoption in entirety.

Having thus described my invention, what I claim as new, and desire to secure by Letters Patent, is—

25 1. In mechanism for corking bottles, the combination with a casing or support, a socket or guide, a plunger and mechanism for causing said plunger to force a cork from said socket into a bottle, of a clamping mechanism 30 comprising laterally-movable members arranged to grasp the upper portion of a bottle, and secure the bottle against vertical movement and in position beneath the casing or support, and mechanism whereby said members may be positively and manually shifted 35 to engage a bottle, said mechanism serving to simultaneously and uniformly move said members toward a bottle.

2. In mechanism for corking bottles, the 40 combination with a casing or support, a socket or guide, a plunger and mechanism for causing said plunger to force a cork from said socket into a bottle, of a clamping mechanism comprising laterally-movable members arranged to grasp the upper portion of the 45 bottle, and secure the bottle against vertical movement and in position beneath the casing or support, said clamping mechanism being sustained by said casing or support, and mechanism 50 whereby said members may be positively and manually shifted toward or from a bottle, simultaneously and uniformly.

3. In mechanism for corking bottles, the 55 combination with a casing or support, a socket or guide, a plunger and mechanism for causing said plunger to force a cork from said socket into a bottle, of a clamping mechanism comprising laterally-movable members arranged to grasp the upper portion of a bot- 60 tle, and secure the bottle against vertical movement and in position beneath the casing or support, and a hand-lever for shifting both of said members.

4. In mechanism for corking bottles, the combination with a casing or support, a socket 65 or guide, a plunger and mechanism for causing said plunger to force a cork from said socket into a bottle, of a clamping mechanism comprising laterally-movable members arranged to grasp the upper portion of the 70 bottle, and secure the bottle against vertical movement and in position beneath the casing or support, said clamping mechanism being sustained by said casing or support, and a hand-lever for shifting both of said jaws. 75

5. In mechanism for corking bottles, the combination with a casing or support, a socket 80 or guide, a plunger and mechanism for causing said plunger to force a cork from said socket into a bottle, of a clamping mechanism comprising laterally-movable members arranged to grasp the upper portion of the bottle, and secure the bottle against vertical movement and in position beneath the casing or support, said clamping mechanism being 85 sustained by said casing or support, and a lever connected with both of said jaws and serving to shift said jaws positively in either direction.

6. In mechanism for corking bottles, the 90 combination with a casing or support, of a plunger guided therein, an operating-lever, said plunger and lever being provided with intermeshing teeth, a socket wherethrough a cork will be forced by said plunger and a pair 95 of jaws pivotally sustained at one side of said casing, and a hand-lever pivotally sustained by said casing for controlling said jaws.

7. In mechanism for corking bottles, the 100 combination with a plunger and an operating-lever operatively connected therewith, of a casing formed of vertical sections, which when secured together, form a support for said lever, and a guide for said plunger, a socket in said casing wherfrom a cork may 105 be forced by said plunger into a bottle, and a pair of jaws pivotally sustained by one casing-section and a lever pivotally sustained by the other of said casing-sections for controlling said jaws. 110

8. In mechanism for corking bottles, the 115 combination with a casing formed of vertical sections, a plunger, a guide in said casing for said plunger, an operating-lever pivotally sustained by said casing, a gear and rack-teeth intermediate said lever and plunger, a socket wherfrom a cork will be forced by said plunger into a bottle, and mechanism for holding a bottle beneath said socket, comprising jaws 120 pivotally sustained by said casing, and a lever pivotally sustained by said casing for controlling said jaws.

ALBERT BAUMGARTEN.
